Primary Examiner — Darlington Ly

(57) **CLAIM**

The ornamental design for a bicycle, as shown and described.

DESCRIPTION

1.1 is a front elevation view of a bicycle embodying my new design;

1.2 is a rear elevation view thereof;

1.3 is a right side elevation view thereof;

1.4 is a left side elevation view thereof;

1.5 is a top plan view thereof;

1.6 is a bottom plan view thereof;

1.7 is a top, rear, and right side perspective view thereof; and

1.8 is a top, front, and left side perspective view thereof.

The broken line showing portions of the bicycle forms no part of the claimed design.
